Edwin Hurd

United States Patent Office.

EDWIN HURD, OF VIRGINIA CITY, NEVADA.

Letters Patent No. 82,821, dated September 22, 1868.

IMPROVEMENT IN OIL-CUP.

The Schedule referred to in these Letters Patent and making part of the same.

TO ALL WHOM IT MAY CONCERN:

Be it known that I, EDWIN HURD, of Virginia City, county of Storey, State of Nevada, have invented an Improved Lubricating-Cup; and I do hereby declare the following description and accompanying drawings are sufficient to enable any person skilled in the art or science to which it most nearly appertains to make and use my said invention or improvements without further invention or experiment.

The object of my invention is to provide an improved lubricating-cup, to be used especially on steam-cylinders, or in any place where the lubricant is introduced against pressure; and it consists of a partially-rotating cylinder between the receiving-cup and the point at which the oil is used. The cylinder has an opening at the top, corresponding with one from the receiving-cup, when in one position, and when the cylinder is rotated to another position, a hole at the bottom allows the oil to flow to its destination, the upper opening being mean-while closed.

To more fully explain my invention, reference is had to the accompanying drawings, forming a part of this specification, of which—

Figure 1 is a side sectional elevation.

Figure 2 is a section taken through C D.

Figure 3 is a section through A B.

Similar letters of reference indicate corresponding parts in each of the figures.

A is a close cylinder, which rotates in a frame, E, turning and working steam-tight on the faces F F'. The cup G, which first receives the oil, has a stem, G', projecting downwards, the lower end of which is bevelled, so as to fit the top of the cylinder at F, and is kept in contact by the nut H pressing on the collar I.

The lower bevelled end of the cylinder is fitted to the bottom of the frame E, as shown at F', also steam-tight. A handle, J, serves to turn the cylinder a, as far as the frame E allows, in either direction. An opening, K, passes from the cup G down through the stem G', and, when the cylinder is in the position shown at fig. 1, this opening connects with the opening L in the top of it, so that the oil or tallow will flow readily into the cylinder, a vent, M, facilitating the flow. In this position the lower opening, N, of the cylinder does not connect with the opening O, and there is no pressure in the cylinder. After the cup G is empty, the cylinder a is turned until the openings N and O connect, when the oil passes down to its destination, the openings K and L being in the mean time closed. A set-screw, P, passes through the side of the frame E, and enters a slot in the stem, G', thus keeping the stem in a line as the nut H is turned down.

In this manner I am enabled to construct a cheap, simple, and perfectly steam-tight lubricating-cup, which will also keep itself tight as it wears, and it cannot be operated wrong by the most ignorant.

Having thus described my invention, I do not claim a hollow cylinder pivoted by means of a central spindle, with air and oil-passages through the pivotal connections, as shown in the patent of M. Vergnes, September 25, 1866, and in others; but

What I do claim, and desire to secure by Letters Patent, is—

The arrangement of the frame E, the hollow cylinder a pivoted within it, and having passages for the reception of oil, for the escape of air, and for the delivery of the oil through the pivots on which it turns, substantially as described.

In witness whereof, I have hereunto set my hand and seal.

EDWIN HURD. [L. S.]
